HYDRAULIC CONTROL DEVICE FOR
A GEAR BOX

Jean-Paul Brunot, Sens, France, assignor to Compagnie de Pont-a-Mousson, Nancy, France, a French body corporate

Filed May 20, 1959, Ser. No. 814,527
Claims priority, application France May 23, 1958
7 Claims. (Cl. 74—750)

The present invention relates to the hydraulic control of road and rail vehicle gear boxes which are of the type having gears always in mesh and in which the speeds are engaged by the immobilization of one or two elements of the gear box and/or by the interconnection of two elements.

A gear box of this type comprises brakes and clutches actuated hydraulically by rams which are supplied with oil under pressure by one or two pumps driven by the engine shaft and by the driven shaft of the gear box. Consequently, the speeds can only be engaged when the pump or pumps are operating.

The object of the invention is to permit engagement of a speed ratio even when the pump or pumps are inoperative, that is, independently of the normal hydraulic circuit.

The invention provides an auxiliary control device for a gear box of the aforementioned type, this device, which permits the engagement of a speed of the gear box when its driving and driven shafts are stationary, comprising in combination an alternating movement pump which is supplied with oil from a reservoir having a pressure head and is actuated by manual operating means, and a ram supplied with oil under pressure by the pump and adapted to permit, when supplied with the oil, engagement of said speed.

Another object of the invention is to provide an assembly of a hydraulic control device for a gear box of the aforementioned type, said control device comprising in combination a main hydraulic control device having rams and supplied by at least one pump controlled by a supply selector, and the aforementioned auxiliary control device whose single ram is connected in parallel with one of the rams of the main control device.

The two rams could be either coaxial or side by side to act on the same end of a speed engaging element or so disposed that one acts on one end and the other on the other end of a floating speed engaging element.

Further features and advantages of the invention will be apparent from the ensuing description with reference to the accompanying drawings to which the invention is in no way limited.

In the drawings:

FIG. 1 is a diagrammatic sectional view of a complete control device consisting of a main device and an auxiliary device according to the invention, having coaxial rams;

FIG. 2 is a partial sectional view of a modification in which the rams are disposed in side by side relation.

FIG. 3 is a sectional view taken along line 3—3 of FIG. 2, and

FIG. 4 is a view similar to FIG. 1, the rams co-operating with the two ends of a floating brake element.

In the embodiment shown in FIG. 1, the invention is applied to a braking device for an element of an epicyclic gear box for engaging a speed ratio, for example the second speed of the gear box.

Let it be supposed that an element or gear 1 of a gear box—only the housing 2 of which has been shown—is disposed at the end of the case of the engine M is to

be immobilized. For this purpose, there is provided a flexible brake segment or element 3 in the form of an open collar surrounding and concentric with the element 1. One of the ends of the segment 3 is fixed to the housing 2 at 4 and the other end 5 is hooked to the stem or rod 6 of a piston 7 pertaining to a main ram V actuating the segment 3. The piston 7 slides in a cylinder 8 which has a vertical axis and is rigid with the housing 2, this cylinder being open at its end adjacent the stem end of the piston 7 and closed at the other end by a special cover 9. This piston is hollow and is caused to slide in the cylinder 8, in opposition to the action of a spring 10 compressed between the end of the cylinder 8 and a face of a flange provided on the piston 7, by the action of oil under pressure. The latter is supplied through a main pipe 11 which extends through the cover 9 and is connected, for example, through the medium of a speed selector S to a single oil pump P¹ driven by the driving or driven shaft of the gear box. In the presently-described embodiment, this pump P¹ is located within the case of the engine M and its shaft 23 is connected to the engine shaft (not shown) which constitutes the input shaft of the gear box.

Disposed within the main ram V and in coaxial relation thereto is an auxiliary ram W. The cover 9 is mounted by a cylindrical skirt 12 which is coaxial with the cylinder 8, open at both ends, and located within the piston 7 which is hollow. Slidable in the skirt or cylinder 12 is a freely disposed piston 13 which is adapted to cause the piston 7 to move under the effect of the pressure of the oil supplied by an auxiliary pipe 14 extending through a screw-threaded plug 15 screw-threadedly engaged in the cover 9. In its inoperative position of rest, the piston 13 is carried by the plug 15.

The pipe 14 is connected to a pump P² or an auxiliary master cylinder comprising a cylinder 16 which is connected by a pipe 17 to an oil reservoir having a pressure head relative to the cylinder 16. A piston 19 is movable in the cylinder 16, under the effect of a push rod 20 actuated by a pedal 21 pivotably mounted on a fixed pin 22, in opposition to the action of a spring 23 compressed between the piston 19 and the end wall of the cylinder 16.

The device operates in the following manner: When the engine of the vehicle is running and the driver wishes to engage a speed of the gear box, he operates the speed selector S in such manner as to supply oil under low pressure by way of the pipe 11 directly into the main ram V. The oil raises the piston 7, the rod 6 and the hook 5 and thus moves the two ends of the brake segment 3 toward each other and causes the segment to tighten round the element 1. The selected speed ratio is thus engaged. During this time, the piston 13 of the auxiliary ram W remains inoperative.

When the driver wishes to change speed, the pipe 11 is connected to the oil exhaust and the spring 10 returns the piston 7 to its initial position and thereby untightens the brake segment 3.

When the engine of the vehicle is not running and cannot be started up by the starter and the driver wishes to engage the second speed by means of the ram including the piston 7, for example for the purpose of towing his vehicle, he depresses the pedal 21 in such manner as to exert force on the piston 19 of the cylinder 16 and thus delivers oil under high pressure through the pipe 14 and into the cylinder 12 of the auxiliary ram W. The piston 13 is then raised. It in turn raises the piston 7 of the main ram V and this tightens the brake

segment 3 and engages the speed in the previously described manner. The driver continues to exert pressure on the pedal 21 until the engine has started up. When this has been obtained, the oil pump P¹ of the engine once more operates and supplies oil under pressure through the pipe 11. This pressure of oil acting on the piston 7 of the main ram V substitutes itself for that acting on the piston 13 of the auxiliary ram W. The driver then releases the pedal 21 which is returned to its initial position by the action of the spring 23. The cylinder 12 is partially emptied and the piston 13 returns to the plug 15.

Thus by means of the invention, which provides a ram W and an additional or emergency oil supply, the engagement of the speed of the gear box is always possible even when the engine is not running and the main ram V cannot be directly supplied with oil under pressure.

Owing to its small volume, the cylinder 12 of the auxiliary ram W is rapidly filled with a single stroke of the pedal 21 and this enables the driver to actuate the device of the invention without fatigue and to act quickly if required.

The driver can therefore use the auxiliary device (W, P²) as an emergency brake by engaging the second speed controlled by this device even if another speed, for example the third or fourth speed, of the gear box is still engaged, which has for effect to immediately block the gear box and energetically brake the vehicle.

FIGS. 2 and 3 show a modification of the invention in which the auxiliary emergency ram W_a is located outside the main ram V, the rods 6 and 6^a of their pistons 7 and 13^a, movable in the cylinders 8 and 12^a, acting on the ends 5 and 5^a of two brake segments or elements 3 and 3^a each of which surrounds half the width of the gear box element or gear 1.

If desired, the two segments 3 and 3^a could form a single segment capable of being actuated by one and/or the other of the rams V and W_a.

In the embodiment shown in FIG. 4, the main ram V and auxiliary ram W^b are so disposed as to act on the opposite ends of the same brake segment or band 3, which is therefore no longer hooked on a projection of the housing 2 as in the first two embodiments. In this modification, the auxiliary ram W^b must be bigger than that of the first two embodiments and must be supplied with liquid at a higher pressure since the tightening force to be exerted on the end 4 of the segment must be greater than in the first two embodiments in view of the direction of rotation of the element 1 indicated by the arrow f in FIGS. 1 and 4.

Although specific embodiments of the invention have been described, many modifications and changes may be made therein without departing from the scope of the invention as defined in the appended claims.

Thus the invention is also applicable to actuation of a clutch or two brake bands or segments simultaneously or to actuation of a brake band and a clutch when these elements are required for engaging a speed.

Having now described my invention what I claim as new and desire to secure by Letters Patent is:

1. In a hydraulic control device for a gear box which has speed engaging elements actuated hydraulically, in combination: on the one hand, a main hydraulic control device comprising main rams for actuating said speed engaging elements, and, on the other hand, an auxiliary control device for engaging one of the speeds even when the main control device is inoperative, said auxiliary control device comprising a pump having an alternating movement, a reservoir for supplying liquid to said pump, means capable of an alternating movement for manually actuating said pump, and an auxiliary ram supplied with oil under high pressure by the pump and so disposed relative to the speed engaging element engaging said speed that when the auxiliary ram is supplied with said

oil it actuates the speed engaging element in the direction for engaging said speed.

5. In a hydraulic control device for a gear box which has speed engaging elements actuated hydraulically, in combination: on the one hand, a main ram for actuating one of said speed engaging elements for engaging the corresponding speed, a pump driven by said gear box for supplying liquid under low pressure to the main ram, and a selector for connecting the output end of the pump selectively to the main ram, and, on the other hand, an auxiliary control device for engaging said speed even when the pump is inoperative, said auxiliary device comprising an alternating movement pump, a reservoir for supplying liquid to said alternating movement pump, means for supplying the liquid to the latter, means capable of alternating movement for manually actuating the alternating movement pump, and an auxiliary ram supplied with oil under high pressure by the last named pump, and so disposed relative to the speed engaging element engaging said speed that when it is supplied with said liquid it causes the actuation of said engaging element for engaging said speed.

2. Hydraulic control device as claimed in claim 2, wherein said auxiliary ram is disposed within said main ram so that when it is supplied with liquid it actuates the speed engaging element in the direction to engage said speed.

25 3. Device as claimed in claim 3, wherein the main and auxiliary rams are of the type having a cylinder and piston, the piston of the main ram being hollow and providing a housing for the auxiliary ram whose piston is so adapted that when it is subjected to the pressure of the liquid it bears against the piston of the main ram.

30 4. Device as claimed in claim 4, wherein a cover closes the cylinder of the main ram and carries within the cylinder of the latter a skirt portion constituting the cylinder of the auxiliary ram.

35 5. In a hydraulic control device for a gear box which has speed engaging elements actuated hydraulically, in combination: on the one hand, a main ram for actuating one of said speed engaging elements for engaging the corresponding speed, a pump driven by said gear box for supplying liquid under low pressure to the main ram, and a selector for connecting the output end of the pump selectively to the main ram, and, on the other hand, an auxiliary control device for engaging said speed even when the pump is inoperative, said auxiliary device comprising an alternating movement pump, a reservoir having a pressure head relative to the pump for supplying the liquid to the latter, means capable of alternating movement for manually actuating the alternating movement pump, and an auxiliary ram supplied with oil under high pressure by the last named pump and so disposed relative to the speed engaging element engaging said speed that when it is supplied with said liquid it causes the actuation of said engaging element for engaging said speed, said speed engaging element being divided into two parts in parallel relation to one another, and the main and auxiliary rams being disposed in side by side relation so as to act on the adjacent ends of said two parts of the speed engaging element.

40 6. In a hydraulic control device for a gear box which has speed engaging elements actuated hydraulically, in combination: on the one hand, a main ram for actuating one of the speed engaging elements for engaging the corresponding speed, a pump driven by said gear box for supplying liquid under low pressure to the main ram, and a selector for connecting the output end of the pump selectively to the main ram, and, on the other hand, an auxiliary control device for engaging said speed even when the pump is inoperative, said auxiliary device comprising an alternating movement pump, a reservoir having a pressure head relative to the pump for supplying the liquid to the latter, means capable of alternating movement for manually actuating the pump, and an auxiliary

ram supplied with oil under high pressure by the pump, and so disposed relative to the speed engaging element engaging said speed that when it is supplied with said liquid it causes the actuation of said speed engaging element for engaging said speed, the main and auxiliary rams being so disposed that one ram acts on one end and the other ram acts on the other end of the speed engaging element. 5
